US0D1084220S

(12) **United States Design Patent** (10) **Patent No.:** **US D1,084,220 S**
(45) **Date of Patent:** **** Jul. 15, 2025**

(54) **FILTER UNIT**

(71) Applicant: **WHIRLPOOL CORPORATION**,

Benton Harbor, MI (US)

(72) Inventors: **David P. Cooper**, Dowagiac, MI (US);
Mark C. Graff, Michigan City, IN (US); **James C. L. Guarino**, Kalamazoo, MI (US); **Chad Rotter**, Saugatuck, MI (US); **Daniel Louis Sigmund**, Golden, CO (US); **Steven J. Kuehl**, Sylva, NC (US); **Joseph R. Peters**, St. Joseph, MI (US); **Justin Glasgow**, Sulphur Springs, TX (US)

(73) Assignee: **Whirlpool Corporation**, Benton Harbor, MI (US)

(**) Term: **15 Years**

(21) Appl. No.: **29/977,771**

(22) Filed: **Dec. 10, 2024**

Related U.S. Application Data

(63) Continuation of application No. 29/890,942, filed on Apr. 28, 2023, now Pat. No. Des. 1,059,542, which is (Continued)

(51) **LOC (15) Cl.** **23-01**

(57) **CLAIM**

The ornamental design for a filter unit as shown and described.

DESCRIPTION

FIG. 1 is a perspective view of a filter unit according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in broken line form no part of the claimed design.

1 Claim, 7 Drawing Sheets

Related U.S. Application Data

a continuation of application No. 18/308,305, filed on Apr. 27, 2023, now Pat. No. 11,806,648, which is a continuation of application No. PCT/IB2022/054007, filed on Apr. 29, 2022.

(52) U.S. Cl.

CPC **B01D 35/30** (2013.01); **B01D 15/30** (2013.01); **B01D 2201/16** (2013.01); **B01D 2201/302** (2013.01)
